UNITED STATES PATENT OFFICE

WILLARD A. ORMSBEE, OF TAUNTON, MASSACHUSETTS, ASSIGNOR TO TAUNTON PEARL WORKS, INC., A CORPORATION OF MASSACHUSETTS

SOFT-COLLAR HOLDER

Application filed July 3, 1930. Serial No. 485,580.

This invention relates to a support for a soft collar, and has for its object to prevent the points or corners of a soft collar from rolling upwardly or spreading excessively apart whereby they may be maintained in the desired position when worn.

A further object of the invention is to provide a soft collar support which will be flexible or elastic so as to bend or give, by pressure of the chin upon the same, and will return to desired position when the pressure is released.

A still further object of the invention is the provision of broad collar fold engaging portions to prevent any distortion of the fold of the collar at the point engaged.

A still further object of the invention is to provide a support which may be worn with a collar holder and which will not interfere 20 with its action.

With these and other objects and advantageous features in view, the invention consists of a novel arrangement of parts more fully disclosed in the detailed description following, in conjunction with the accompanying drawings, and more particularly set forth in the appended claims.

In the drawings:

Fig. 1 is a perspective view of the collar showing in dotted lines the position of the holder with reference thereto;

Fig. 2 is a plan view of the holder;

Fig. 3 is an edge view thereof;

Fig. 4 is a side elevation showing the holder as engaging the fabric of a collar to be retained in position;

Fig. 5 is a section on line 5—5 of Figure 2;

Fig. 6 is a perspective view of a portion of the wire core;

Fig. 7 is a perspective view of a portion of the covering for the core;

Fig. 8 is a perspective view of a modified form of covering for the core; and

Fig. 9 is a section of the wing on line 5—5 of Figure 2 showing the same before its attaching portion is bent about the core and its covering.

Soft collars when worn often have a sloppy appearance by reason of the points or corners becoming turned or rolled upwardly and

outwardly, which occurs frequently when worn by a person assuming a sitting position, as at a desk or the like, with the head bent forward; and in order that the corners or points of the collar may be retained straight to preserve a stiff collar neater appearance with soft collar comfort, I have provided a support which is positioned beneath the necktie and along the inside edge of the collar to engage the same and maintain it in desired position, the same being sufficiently flexible and elastic to yield, due to pressure of the chin when the head is bent forward and return the collar to the desired position when pressure thereon is released; and the following is a detailed description of the present embodiment of this invention illustrating the preferred means by which these advantageous results may be accomplished.

With reference to the drawings, 10 designates the core which I have found convenient to form of resilient steel wire, the same being bent into a generally U-shape form, as illustrated in Figure 2, which is covered by a tubing of helically wound wire 11, extending substantially the full length of the U-shape core. The ends of the tube are received within cups 12 which are retained in position on the core by the loop 13 thereof engaging the cups as at 14. The ends of the core are sharpened as at 15 to stick into the fabric 16, as shown at 17 in Figure 4, and are limited in the amount they may extend into the fabric by the loop 13.

The U-shape device provides a body member or cross bar 18 with legs 19 extending therefrom, and adjacent the juncture of the body and legs I have provided wings 20, preferably formed of sheet metal with a portion 21 folded about the core and its covering at this point of juncture. The wings are cut out forming an open center portion 22 and are provided with a rib 23 raised from the stock to stiffen the same against bending.

In positioning the device for use, the body portion 18 is positioned beneath the knot 24 of the tie with the wings 20 engaging the fold 25 of the collar 26. The sharpened points 15 of the legs 19 are then caused to project into the fabric of the collar to a limited extent so

as not to extend entirely therethrough, which mounts the device in working position to hold the points of the collar straight. The edges 27 of the wing portions are elongated sufficiently to extend a sufficient distance along the fold 25 of the collar to prevent deflection of the fold and preserve the appearance of the collar.

The helically formed tube which covers 10 the core supports and strengthens the same, and for this may be substituted a tube formed of mesh as illustrated at 28 in Figure 8, if desired.

It is convenient that the tubular covering 15 extend substantially from end to end of the device, although the flexed and exposed portions of the core only need be covered.

The body 18 is curved sufficiently to conform to the shape of the collar for comfort 20 in use, and the legs 19 may be at varying angles and the device of varying heights or widths to conform to different styles of collars.

While I have described certain construction forms which embody the principles of 25 my invention, it is obvious that other desired changes in arrangement may be made within the spirit and the scope of the invention as defined in the appended claims.

30 I claim:

1. A soft collar support comprising a body member provided with legs extending therefrom, means adjacent the ends of the legs for engaging and being retained in a soft 35 collar adjacent the points or corners thereof, said legs comprising a resiliently flexible core with a helical wire covering thereon.

2. A soft collar support comprising a body member provided with legs extending therefrom, means adjacent the ends of the legs for engaging and being retained in a soft collar adjacent the points or corners thereof, and wings in line with said legs presenting a broad engaging surface secured adjacent the 45 juncture of said body member and legs and projecting thereabove to engage the fold of the collar.

3. A soft collar support comprising a body member provided with legs extending therefrom, means adjacent the ends of the legs for engaging and being retained in a soft collar adjacent the points of corners thereof, and sheet metal wings lying in substantially the plane of said body member and 55 legs and secured adjacent their juncture to project therefrom and engage the fold of the collar, and ribs on said wings to stiffen the same.

4. A soft collar support comprising an inverted generally U-shaped wire core provided with means at its ends to engage and be retained in the collar, and a flexible covering on said core.

5. A soft collar support comprising an inverted generally U-shaped wire core provid-

ed with means at its ends to engage and be retained in the collar, a flexible wire covering on said core, and wings secured to said covering and core and projecting thereabove to engage the fold of the collar.

6. A soft collar support comprising a generally U-shaped wire core provided with means at its ends to engage and be retained in the collar, a tubular wire covering on said core, caps at the ends of said covering held in position by said collar engaging means, and wings secured to said covering and core and projecting therefrom to engage the fold of the collar.

7. A soft collar support comprising a generally U-shaped wire core coiled at its ends and sharpened at its extremities to engage and be retained in the collar, a covering of helical wire on said core, caps at the ends of said covering retained in position by said coiled ends, and wings presenting broad engaging surfaces having portions folded about said covering and core and projecting therefrom to engage the fold of the collar.

8. A soft collar support comprising a generally U-shaped wire core coiled at its ends in a plane substantially the plane of the wire and sharpened at its extremities to engage and be retained in the collar, and a tubular wire covering on said core.

9. A soft collar support comprising a generally U-shaped wire core coiled at its ends in a plane substantially the plane of the wire and sharpened at its extremities to engage and be retained in the collar, a tubular wire covering on said core, and wings secured to said covering and core and projecting thereabove to engage the fold of the collar.

In testimony whereof I affix my signature.

WILLARD A. ORMSBEE.
